Primary Examiner — Cynthia Ramirez*Assistant Examiner* — Xavier Marti-Santos(74) Attorney, Agent, or Firm — Banner & Witcoff, Ltd.(57) CLAIM

The ornamental design for a couch, as shown and described.

DESCRIPTION

FIG. 1 is a front, left-side perspective view of a couch showing my new design;

FIG. 2 is a front perspective view thereof;

FIG. 3 is a front, right-side perspective view thereof;

FIG. 4 is a rear, left-side perspective view thereof;

FIG. 5 is a rear perspective-view thereof;

FIG. 6 is a rear, right-side perspective view thereof; and,

FIG. 7 is a right-side perspective view thereof.

The broken lines in the figures are for the purpose of illustrating portions of the sofa, which form no part of the claimed design.
